CLAIM

The ornamental design for a card holder, as shown and described.

DESCRIPTION

The claimed design is intended to be used in a handbag or tote bag.

FIG. 1 is an elevational view of a card holder showing my new design;

FIG. 2 is a perspective view thereof shown in its environment; and,

FIG. 3 is section view taken along line 3—3 of FIG. 2.

The claimed design is intended to be used in a handbag or tote bag.

The broken line showing of the remainder of the bag in FIGS. 2 and 3 is for illustrative and intended use purposes only and forms no part of the claimed design.

1 Claim, 2 Drawing SheetsFIG. 1

FIG. 3
